UNITED STATES PATENT OFFICE.

HERBERT B. SABIN AND ORRIN C. SABIN, OF CLEVELAND HEIGHTS, OHIO.

DEVICE FOR APPLYING GLAZING COMPOUNDS AND THE LIKE.

1,343,408.

Specification of Letters Patent. Patented June 15, 1920.

Application filed June 13, 1919. Serial No. 304,077.

To all whom it may concern:

Be it known that we, HERBERT B. SABIN and ORRIN C. SABIN, citizens of the United States, and residents of Cleveland Heights 5 village, county of Cuyahoga, State of Ohio, have jointly invented a new and useful Improvement in Devices for Applying Glazing Compounds and the like, of which the following is a specification, the principle of the 10 invention being herein explained and the best mode in which we have contemplated applying that principle, so as to distinguish it from other inventions.

The present invention relates to devices 15 for applying glazing putty or like compounds and it relates more particularly to a gun which may be operated by one hand, the operating mechanism being arranged so that the glazier can expel the entire charge from 20 the gun without using both hands. It is particularly intended for use with the putty or compound used for filling the edges along panes of glass, such as is commonly used in green house construction, and is so arranged 25 as to be suspended from the one arm of the operator, the mechanism for expelling the grease being operated by the hand, thus leaving the other hand and arm entirely free. To the accomplishment of the foregoing and related ends, said invention, then, 30 consists of the means hereinafter described and particularly pointed out in the claims.

The annexed drawing and the following 35 description set forth in detail certain mechanism embodying the invention, such disclosed means constituting, however, but one of various mechanical forms in which the principle of the invention may be used.

In said annexed drawing:—

40 Figure 1 is a side elevation of our improved device; Fig. 2 is a longitudinal section through the same; Fig. 3 is a view of the pawl in its latch-releasing position; Fig. 4 is a bottom plan view of the nozzle; and Fig. 5 is a section on the line 5—5, Fig. 4.

In general construction, the gun consists 45 of the usual barrel or cylinder 1 having threaded ends 2. On the forward end a cap 3 is threaded, which cap is provided with a discharge nozzle 4 to be described in detail hereinafter. A rear cap 5 is threaded on the other end of the barrel, this cap having an aperture through which extends the usual 50 plunger or piston rod 6. Within the barrel or cylinder is mounted a suitable piston 7 which in the form shown consists of two

plates 8 with a cork disk 9 between the same, the piston rod 6 extending through aligned apertures in the disk and plates. The rod is threaded at its forward end and a nut 10 is 60 mounted thereon to clamp the plates tightly upon the disk and to hold the rod securely to the piston. This particular structure is not important and any other suitable piston may, of course, be used.

65 At the forward end of the barrel a handle 14 is mounted, the handle being U-shaped in section and having a rearwardly extending upper end or projection 15 adapted to rest upon the hand of the operator to carry 70 the weight. This handle is provided near the cylinder with an aperture 16 through which is movably mounted a rod 17. This rod extends in front of the handle and is provided with an upturned end 18 lying approximately parallel to the handle. Encircling the rod between the upturned end and the interior of the handle is a coiled spring 19 secured in position by a pin 20, the spring being adapted to maintain the rod in its forward 75 position.

The rod 17 extends rearwardly along the cylinder, being bent to conform to the shape of the same and having a drop portion 21 so as to bring the rod to the rear at a point out of line with the forward portion of the rod. At its rear end, the rod extends outwardly from the barrel and is pivotally connected to an arm 22 which is in turn pivotally mounted on a lug 23 carried by the rear cap. 80 This arm is formed of two plates so spaced as to receive the rod therebetween, as well as the plunger or piston rod. In the other end of the arm, a movable pawl 24 is mounted, the pawl being normally in engagement with the series of teeth 25 formed on the plunger or piston rod. A flat spring 26 is carried by the arm and normally holds the pawl in its operative position. The spring as shown is so positioned that it will also hold the pawl 85 out of engagement in the position shown in Fig. 4, the inturned end 45 of the spring limiting the upward position of the pawl.

90 On the rear face of the cap, a latch 27 is attached by means of a screw 28 passing through an elongated aperture in the latch, thus allowing limited movement of the same. On a boss 29 on the cap, a flat spring 30 is mounted, the spring extending over the upper face 31 of the latch and tending to maintain it in its position engaging the teeth on the piston rod. The latch is provided 95 100 105 110

with a shoulder 46 which is adapted to be engaged by the pawl in its upper position. Movement of the rod 17 will then force the latch upwardly out of engagement with the teeth on the piston rod and the plunger may then be withdrawn by means of the small hand 47.

At the rear end of the cylinder a strap 32 is provided, which will be riveted or otherwise securely fastened to the cylinder or cap. The upwardly extending loop of the strap is adapted to encircle the arm of the operator and the strap may be adjusted to fit the arm snugly by means of the buckle 33.

15 In operating the gun, the user extends his arm through the strap and grasps the handle, the extending piece of the latter resting upon the hand and carrying the weight. By extending his fingers, the operator 20 grasps the upturned end of the rod and by moving the rod toward the handle, operates the arm at the rear to force the piston forwardly along the barrel by means of the pawl and ratchet mechanism. At each successive movement of the rod, the pawl will 25 engage with and force the plunger rod into the gun, the latch preventing return movement of the plunger during the return movement of the rod and pawl. At the forward end of the movable rod, just rearwardly of the handle, are a series of apertures 40 through which a cotter pin 41 may be placed to limit the forward aperture and each movement of the rod forces the plunger into 30 the barrel a distance equal to one of the teeth on the piston rod. By moving the pin to the rear apertures, the movement of the plunger may be increased, as will be readily understood.

35 40 The forward cap is provided with a nozzle 4 which has its tip cut away at an angle as at 42, the sides of the cut-away portion being faced off to provide a tip having an angular bottom, the two sides 43 lying approximately 90° from each other. In use on green houses, the tip is moved along the junction of the stringer and the glass, which are at approximately 90° to each other, thus allowing the grease or putty, as it is called, 45 to flow out along the joint in the correct position to form a satisfactory sealing strip of putty. The upper portion 44 overhangs the angular bottom and allows the putty to flow out in the correct form to fill the space between the glass and sash.

50 The gun is carried and operated by one arm and the user can also drop the handle of the gun, allowing it to swing from the arm when it is necessary for him to use both hands. When the gun is empty the spring holding the pawl is released and the pawl turned upwardly. The operator then grasps the handle and by moving the operating rod, forces the pawl into engagement with the 55 latch to release the piston rod so that it

may be returned to its filling position. The nozzle cap will then be removed and the gun refilled.

A very convenient and easily operated gun is thus obtained and one which the operator can use with one hand. The grease can be readily expelled, the adjustment of the rod helping to determine the speed of flow. When it is necessary, the operator may use both hands, allowing the gun to 75 hang from the strap. As the grease may be expelled either intermittently or continuously as desired, a very satisfactory gun is secured. In filling the gun, the nozzle being removed, the operator holds the gun upright by the handle and it is then easily filled, as it is in the most convenient position for this operation.

80 Other modes of applying the principle of our invention may be employed instead of the one explained, change being made as regards the mechanism herein disclosed, provided the means stated by any of the following claims or the equivalent of such stated means be employed.

90 We therefore particularly point out and distinctly claim as our invention:—

1. In a device of the character described, the combination of a barrel, a piston therein, a toothed piston rod, a handle on said barrel near the forward end thereof, and operating means including pawl and ratchet mechanism adapted to engage with the teeth on said piston rod to move the same, said operating mechanism being disposed adjacent said handle.

105 2. In a device of the character described, the combination of a barrel, a piston therein, a toothed piston rod, a handle on said barrel, operating means including pawl and ratchet mechanism adapted to engage with the teeth on said piston rod to move the same, said operating mechanism being disposed in operative relation to said handle, and carrying means mounted on said barrel 110 and adapted to encircle the arm of the operator.

115 3. In a device of the character described, the combination of a barrel, a piston therein, a toothed piston rod, a handle on said barrel near the forward end, carrying means on said barrel near the rear end, and operating mechanism disposed adjacent said handle and including pawl and ratchet mechanism for operating said piston rod.

120 4. In a device of the character described, the combination of a barrel, a piston therein, a toothed piston rod, a handle on said barrel near the forward end, said handle having a rearwardly extending portion adapted 125 to rest upon the hand of the operator, carrying means on the rear end of the barrel adapted to encircle the arm of the operator, and operating mechanism including a pawl and means for engaging the same with said 130

toothed piston rod, and an operating rod disposed adjacent to and in front of said handle.

5. In a device of the character described, the combination of a barrel, a piston therein, a toothed piston rod, an apertured handle mounted on said barrel, operating mechanism including a rod mounted through said handle and having its forward end adjacent 10 and parallel to said handle, means including a pawl in operative relation to said rod and said toothed piston rod whereby movement of the former operates the latter, and a latch adapted to normally engage said piston rod to prevent return movement of the same.

6. In a device of the character described, the combination of a barrel, a piston therein, a toothed piston rod, an apertured handle mounted on said barrel, operating mechanism including a rod mounted through said handle and having its forward end adjacent and parallel to said handle, means including a pawl in operative relation to said rod and said toothed piston rod whereby movement of the former operates the latter, a latch adapted to normally engage said piston rod to prevent return movement of the same, and a strap on said barrel near the rear and 25 adapted to encircle the arm of the operator to carry the weight.

7. In a device of the character described, the combination of a barrel, a piston therein, a toothed piston rod, an apertured handle mounted on said barrel, operating mechanism including a rod mounted through said handle and having its forward end adjacent and parallel to said handle, means including

a pawl in operative relation to said rod and said toothed piston rod whereby movement 40 of the former operates the latter, a latch adapted to normally engage said piston rod to prevent return movement of the same, an adjustable strap on said barrel near the rear and adapted to encircle the arm of the operator to carry the weight of said gun.

8. In a device of the character described, the combination of a barrel, a piston therein, a toothed piston rod, an apertured handle on said barrel, operating mechanism including 50 a rod mounted through said handle and having its forward end adjacent and parallel to said handle, a movable arm connected to said rod, a pawl carried by said arm and adapted in its normal position to engage 55 said toothed piston rod, a latch adapted to engage said toothed piston rod to prevent return movement of the same, said latch having a shoulder, said pawl being also adapted to be engaged under the shoulder of 60 said latch to move the same out of engagement with said piston rod to allow the latter to be returned to its filling position.

9. A nozzle for a glazing gun comprising a spout having an overhanging end, the 65 under portion of the spout being faced off to provide a rectangular point.

10. A nozzle for a glazing gun comprising a spout having a rectangular lower portion adapted to fit the angle between the glass 70 and sash and an overhanging upper portion adapted to spread the glazing material in to such angle in the desired form.

Signed by us, this 9th day of June, 1919.

HERBERT B. SABIN.
